(57) **CLAIM**

The ornamental design for an upper portion of a container, as shown and described.

DESCRIPTION

FIG. 1 is a perspective view of an upper portion of a container showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of the interior of the bottom of the container, the container threads and the lower portion of the container is for illustrative purposes only and forms no part of the claimed design.
